UNITED STATES PATENT OFFICE.

EDWARD EMMERS, OF ROYERSFORD, PENNSYLVANIA.

WOMAN'S UNDERVEST.

1,204,657.

Specification of Letters Patent. Patented Nov. 14, 1916.

Application filed May 11, 1915. Serial No. 27,291.

To all whom it may concern:

Be it known that I, EDWARD EMMERS, a citizen of the United States, and resident of Royersford, county of Montgomery, and 5 State of Pennsylvania, have invented an Improvement in Women's Undervests, of which the following is a specification.

The object of my invention is to provide a construction of undervests for women 10 which, by simple adjustment of the shoulder straps, will provide either of two shapes of bust, namely a low V cut or a high straight front as may be desired; and furthermore, will provide a broad or relatively narrower 15 garment at the shoulders to suit persons of different stature.

My object is further to so construct the garment that the interchange from high to low bust arrangement may be had with 20 shoulder straps which are continuous over the shoulders; and further to provide means for independent adjustment of the width of the bust and back of the high bust portions whereby one part is not affected by any 25 tension upon the other.

In embodying my invention in practical form, I employ a knitted fabric in tubular form, in which the bust portion is cut off transversely to the length of the tubular 30 fabric, and said fabric further cut in the direction of the length of the same to provide four corners each formed by the juncture of a part of the transverse upper or bust edge of the tubular fabric and one of 35 the longitudinal edges formed by the longitudinal cuts, and to two of these corners, diagonally arranged, I provide independent shoulder straps, the free ends of which may be detachably coupled respectively with the 40 other diagonally arranged corners in one way to provide a garment with straight bust and back, and coupled in another way to form, of the arm portions, a V cut bust and back, and provide from the straight 45 front and back portions, laterally extending arm sockets below the shoulder straps.

In further embodiment of my invention I employ only two shoulder straps, respectively on the diagonal corners formed by the 50 juncture of the chest and back edges with the arm hole portions, said straps having free ends adapted to be respectively coupled with either of the remaining similar corners of the garment which have no straps, according 55 to whether the garment is to be arranged for high or low bust use.

My invention also comprehends details of construction which, together with the features above specified, will be better understood by reference to the drawings, in 60 which:

Figure 1 is a perspective view of my improved undervest when the shoulder straps are so coupled as to provide a high straight bust and back; Fig. 2 is a similar view of 65 the same garment when the shoulder straps are coupled in a different way to lower the cut of the bust and give it a V shape; Fig. 3 is a perspective view corresponding to a portion of Fig. 1 with the arm straps uncoupled; and Fig. 4 is a diagrammatic view 70 illustrating the manner of cutting the tubular knitted fabric from which the body of the garment is made.

2 is the body of the garment and, ordinarily, is made of tubular ribbed knitted fabric formed upon a circular knitting machine. A section of this knitted tube is cut transversely to form the substantially straight bust edges 5, and is split on diametrically opposite sides to form the edges 3 constituting the lower parts of the arm holes, the said edges 3 meeting at the lower parts 4, namely those portions at the bottom of the slits above mentioned. Extending upward from alternate junctures of the edges 3 and 5, I provide shoulder straps 6 and 7, these being two in number and preferably formed of open or lace work which may be continued as a border edge along 80 the edges 3 and 5 as shown, and in which tapes or ribbons may be threaded. The free ends of the shoulder straps may be formed of plain fabric and adapted to be detachably united to the remaining diagonally 85 arranged corners of the body by buttons, fasteners or like devices.

The diagonally arranged corners 8 and 9 formed by the juncture of the edges 3 and 5 are not provided with shoulder straps as 100 are the other diagonally arranged corners. These corners may be provided with buttons 10 to be received in the button holes 11 of the free ends of the shoulder straps 6 and 7. These corners may, if desired, be reinforced 105 by the pieces 12 placed over them and stitched in place and which will also act as a binding for more securely attaching the button and the lace edging of the edges 3 and 5 of the garment. It will now be seen 110 that when the two shoulder straps 6 and 7 are extended over in opposite directions and

coupled with the corner portions 8 and 9 respectively as in Fig. 1, the bust and back portions 5 will be high; but when these straps are respectively reversed in their connections so that the strap 6 connects with corner 9 and strap 7 with corner 8, as in Fig. 2, we will have the arm hole portions 3 become low or V cut bust and back portions, and the parts 5 become the arm hole portions.

The shoulder straps 6 and 7 are continuous over the shoulders so as to have an unobtrusive effect, especially when the outer garment is of transparent material or more or less low necked, such as when the straps might show. Because of the continuity of the straps over the shoulders, they may be made more artistic and delicately formed than if the adjustability was formed in the strap itself at top of the shoulder. The tapes or drawing ribbons may be arranged as follows: A short tape 13 may have one end secured to the corner 8 of the garment and extending through the open lace edging, terminate in a free end at the middle of the bust. A long tape 14 may have one end secured in the free end of the shoulder strap 7 and extending through the open work edging, terminate in a free end at the middle of the bust. The two free ends of the tapes 13 and 14 may be adjustably tied at 15 to regulate the width of the bust. It is also evident that this tape 14 may be secured at the base of the shoulder strap at 16 against being drawn through the lace edging. In this way the shoulder strap will not be drawn or distorted by any adjustment of the tapes. The same general arrangement of tapes is provided for the back portion of the garment, 17 being the short tape and 18 the long tape extending through the shoulder strap 6 and preferably secured at 20. The free ends of the tapes 17 and 18 may be adjustably tied at 19 to adjust the width of the back independently of the bust. In this way the garment may be adapted to large or small busted persons. The arm hole portions 3 may have open work lace edging and this may extend along the shoulder straps, and in such lace edging may be arranged the tapes 21 whose ends are respectively secured in the corners 8 and 9 and free ends of the shoulder straps 6 and 7. These tapes do not require adjustability because, when the garment is arranged for low bust and back, as in Fig. 2, the edges 3, being in the length of the knitted fabric, are not very elastic and hence hold close to the chest and back of the wearer and fit women of varying sized busts by the arm hole portions yielding proportionally. In the case of high bust adjustment, the edges 5 are transverse to the direction of the length of the knitted fabric and hence normally have great elasticity and should be provided with regu-

lating means for adjustment, as are provided in this case by the tapes 13, 14, 17 and 18 adjustably tied in pairs as shown.

It will be seen by comparing Figs. 1 and 2, that the general shape of the bust and arm portion of the undervest has been completely changed by the simple act of coupling the shoulder strap portions in different combinations. Not only does the high straight bust become changed to a low V cut bust, but where the material of the former provided for a full bust, the latter will give a somewhat tighter bust structure but with more fullness under the arms. In those cases where no shoulder straps are desired, or when using the vest as a corset-cover, the straps 6 and 7 are not coupled, but instead, are turned down so as to be invisible and leave the shoulders entirely free, and this too, without having undesirable material under the arms as has heretofore been necessary.

In place of using buttons and buttonholes, as shown in Figs. 1 and 2, I may employ any other suitable fasteners, such as those used upon gloves, etc. While it is preferable to provide the straps with fasteners of some kind, such fasteners may be omitted and fancy pins of artistic or other nature may be employed instead, if so preferred.

I have shown my improved undervests in the form I prefer, for general use, but I do not restrict myself to the details, as these may be modified without departing from the spirit of the invention.

Having now described my invention, what I claim as new and desire to secure by Letters Patent is:—

1. As an article of manufacture, an undervest for women made of knitted fabric in tubular form having its upper or bust end cut transversely across the length of the fabric and having said end also cut longitudinally on diametrically opposite sides to provide arm hole portions and four corner portions constituting the junctures of the arm portions with the bust and back portions, and having two of the corner portions which are diagonally arranged each provided with integral shoulder straps extending therefrom and each having a free end said shoulder straps being of sufficient length to respectively extend completely over the shoulders in opposite directions and respectively connect directly with either of the remaining two diagonally arranged corners of the garment, said straps arranged to be coupled with either of the corner portions to provide high bust and back portions or low bust and back portions as desired.

2. As an article of manufacture, an undervest for women made of knitted fabric in tubular form having its upper or bust end cut transversely across the length of the fabric and having said end also cut longi-

itudinally on diametrically opposite sides to provide arm hole portions and four corner portions constituting the junctures of the arm portions with the bust and back portions, and having two of the corner portions which are diagonally arranged provided with independent shoulder straps extending therefrom having free ends, said shoulder straps being of sufficient length to respectively extend continuously over the shoulders in opposite directions and respectively connect with either of the remaining two diagonally arranged corners of the garment, and said straps arranged to be coupled with the corner portions to provide high bust and back portions or low bust and back portions as desired, and detachable fastening devices one portion of each of which is arranged on the end of each of the shoulder straps and the other coacting portion on the corners of the garment which have no shoulder straps.

3. As an article of manufacture, an under-vest for women made of knitted fabric in tubular form having its upper or bust end cut transversely across the length of the fabric and having said end also cut longitudinally on diametrically opposite sides to provide arm hole portions and four corner portions constituting the junctures of the arm

portions with the bust and back portions, and having two of the corner portions which are diagonally arranged provided with independent shoulder straps extending therefrom having free ends said shoulder straps being 35 of sufficient length to respectively extend continuously over the shoulders in opposite directions and respectively connect with either of the remaining two diagonally arranged corners of the garment, and said 40 straps arranged to be coupled with the corner portions to provide high bust and back portions or low bust and back portions as desired, and two pairs of drawing tapes one pair for the bust portion and the other pair 45 for the back portion one end of one of said tapes of each pair being connected to a corner having no shoulder strap and the other tape of each pair extending to the corner provided with a shoulder strap, and said 50 pairs of drawing tapes having free ends at the bust and back respectively for adjusting the width of the garment.

In testimony of which invention, I hereunto set my hand.

EDWARD EMMERS.
